UNITED STATES PATENT OFFICE

2,133,567

WRINGER

Julian L. Perkins, West Springfield, Mass.

Application November 10, 1936, Serial No. 110,049

8 Claims. (Cl. 68—253)

This invention relates to improvements in wringers.

The principal object of the invention is directed to the provision of a wringer which is characterized by a manual member that is movable from a neutral inoperative position to an operative position to put the rolls under tension, or to release the pressure, in combination with driving mechanism for driving the roll or rolls in opposite directions which includes a shiftable member movable independently of the manual member between operative and inoperative positions but movable by the manual member from an operative position to an inoperative position to bring about stopping of the rolls and releasing of pressure.

By means of the novel features of the invention the operator may move the manual member to an operative position to set the rolls under pressure without engaging the driving mechanism. With the rolls under tension the driving mechanism may then be engaged. In case the hand or other part of the operator becomes caught in the rolls the operator by bringing up against the manual member may swing it quickly to release the pressure and simultaneously stop the driving mechanism.

In the event it is desired to reverse the direction of rotation of the rolls or to stop them without releasing the pressure, the shifter may be moved for that purpose independently of the manual member.

Altogether the driving mechanism may be engaged and disengaged by movements of the shifter quite independently of the movements of the manual member which is movable for setting the rolls under tension or for releasing them. Where the manual member is in an operative position with the rolls under tension and the shifter in an operative position with the rolls being driven the rolls are released from tension and the driving mechanism is disengaged by a simple movement of the manual member to its neutral inoperative position.

Heretofore it has been customary to bring about operation of the driving mechanism by all movements of the manual member. This is objectionable for the reason when one becomes caught between the rolls the manual member may be swung from operative position to and through its neutral inoperative position and beyond to operative position so that the operator is still caught between the rolls only under worse conditions because a part having passed between the rolls

must now pass therebetween in a reverse direction.

Furthermore, in the prior art wringers where clothes have become wound about the rolls and it is desired to reverse the rolls to unwind the clothes it cannot be done without releasing the tension because it is difficult if not impossible to restore the tension when released with clothes around a roll or rolls. According to this invention the rolls may be reversed without releasing the tension.

Various and numerous objects and advantages of the invention will be hereinafter more fully referred to in connection with the accompanying description of the preferred form thereof. In the drawings:

Fig. 1 is a side elevational view of a wringer embodying the novel features of the invention;

Fig. 2 is a sectional elevational view taken on the line 2—2 of Fig. 3;

Fig. 3 is a longitudinal sectional elevational view through the head end of the wringer;

Fig. 4 is a sectional plan view on the line 4—4 of Fig. 3;

Fig. 5 is a similar view on the line 5—5 of Fig. 3; and

Fig. 6 is an inverted plan view taken through the shifter member.

Referring now to the drawings in detail the invention will be fully described.

The wringer comprises in general a head 2, an end frame part 4 connected to the head in some suitable manner as by a longitudinal member 6.

The head is in the form of a housing 8 having a longitudinal bore 8 and a vertical bore 10 in a post part 12. The post is adapted to be supported by the column of a washing machine or the like with which the wringer is associated. A drive shaft is represented by 14 which may be journaled for rotation by a bearing 16. A driving element 18 in the form of a pinion is carried by shaft 14.

A pair of driven elements in the form of gears 16' provided with teeth 20 are fixed as by pins 22 to a shaft 24. The gears reciprocate in the bore 8 of the head and accordingly as they are moved from the neutral position shown in Fig. 3 to the right or left to an operative position one or the other gear 16' is engaged with the pinion 18. With shaft 14 rotating in a certain direction the shaft 24 may be rotated in either direction by engaging a certain gear 16' with pinion 18.

The shaft 24 has an end socket member 26 rotatable in a bushing 28 secured to the housing and it has a socket 29' to receive an end 30 of a

shaft for a lower roll 28. A key or pin 31 of shaft end 30 is receivable in slots 32 associated with socket member 26. The opposite end of the shaft for roll 28 is journalled in end part 4.

5 The receivers to be described are mounted in the head and end frame 4 similarly to those shown in U. S. Letters Patent #1,906,406 to J. L. Perkins which also shows how the lower roll and shaft are mounted in the wringer. The receivers 10 being similar the one associated with the head only will be described.

The head has a vertically disposed channel part 34 and in this there is a receiver 36 slidable up and down. Rods 38 fixed to the receiver slide in 15 bosses 40 associated with channel 34 and springs 38 around the rods are disposed between the bosses 40 and ends 42 of the rods. These springs 20 resist upwardly movements of the receiver.

25 Connecting slots 44 and 45 are provided on the inner face of the receiver 36 and near the lower part there are cam faces 46 and a slot 48. A receiver 50 similar to the receiver 36 is mounted in end frame part 4 and this is provided with slots and cam surfaces like those described with reference to receiver 36.

30 A manual member 56 is provided which has a manually engageable longitudinal part 58 and end parts 60. An upper roll 62 is associated with the manual member 56 and the roll and manual member constitute a separate unit or frame. A projection on each end of the manual member such as 64 is provided as is another stud 66 thereabove. The lower one may be provided by extending the ends of the shaft for roll 62 beyond 35 parts 60.

40 The manual member unit, where the upper slots 44 are provided in the receiver, is inserted in the wringer by holding the manual members so the projection 64 and stud 66 pass into and through slots 45 into slots 46 of the receivers. Then the manual member is swung so that it is directly over roll 62 and it is lowered until roll 62 comes to rest on roll 28. The projections 64 and studs 66 are shown in Fig. 2 as they appear 45 with reference to the slots of the receivers when the manual member is directly over the roll 28 in neutral inoperative position.

46 To operate the wringer the manual member is swung to one side or the other from a central 50 neutral inoperative position. As it swings the parts 60 on the ends 66 of the manual member engage the cam surface 46 of the receivers so that the manual member is releasably locked to the receivers. According to the arrangement of 55 the springs the rolls, when the manual member is locked to the receivers, are under more or less tension and exert yielding pressure as material or clothes are passed between the rolls. The construction described and its function is similar to 60 that described in the patent referred to and need not be described more in detail here. When it becomes necessary or desirable the manual member may be released so as to release the pressure exerted by the springs, by the operator bringing 65 up against the manual member with the arm or hand to swing it to its neutral position.

70 The swinging of the manual member from its neutral inoperative position to operative position is independent of any driving mechanism so the manual member may be releasably locked in operative position without danger of the operator becoming caught or injured. As will presently appear, the driving mechanism is set in operation independently of the manual member yet when 75 the manual member is swung to inoperative neu-

tral position the driving mechanism is automatically disengaged. In this way it is possible for an operator to release the rolls and stop their rotation.

5 A slide 78 is fixed to a collar in which shaft 24 is rotatable and is slidable in a slot 73 of the head. As it slides it moves the collar 71 and one or the other of the gears 16 into engagement with pinion 18.

10 A shifter 72 is oscillatable on bushing 28 and 10 it has a part 74 provided with an angularly disposed cam slot 75 (see Fig. 6) in which is a pin or roller 76 associated with slide 78. As the shifter is oscillated in one direction or the other, by means of the cam 75 slot and pin 76, the slide is 15 reciprocated back and forth to engage and disengage the driving mechanism. An extension 78 of the slide is provided with a bore 80 in which is slidable the head 82 of a plunger 84 and the flanges 86 of a plunger 88. A spring 89 is disposed between flange 86 and head 82 and a pin 90 is carried by the extension 78 between the flanges 86. Abutments 92 are associated with the head against which the outer ends of the plungers 84 and 88 abut. The spring and plungers function to urge the collar 71 and gears to 25 their neutral inoperative position.

30 An operating member 98 is associated with member 72 and a bolt 100 is slidable in said member. The bolt 100 has a shank 102 which projects outwardly from the rear end of the shifter and a depending part fixed thereto and which may be in the form of a pin 104 extends downwardly from the shank 102. A cam member 106 having a curved cam part 107 is secured to the 35 housing and a spring 108 urges the bolt 102 forwardly or to the right to cause the pin 104 to follow the cam 107.

40 The forward end of the bolt 100 has lips 108 at its ends as shown in Fig. 4.

45 A rocker 110 is oscillatable on bushing 28 and its upper end has a converging slot 112 for receiving a stud 66 of the manual member whereby it is swung back and forth by the manual member 56. A stud 114 extends rearwardly from the rocker 110 for engagement with the lips 108 of the bolt 100. This rocker 110 is moved by the 50 manual member in such a way that it is associated therewith, and in some cases may be dispensed with by arranging a projection such as 114 on the manual member itself so that it may engage the lips of the bolt.

55 As previously described, the manual member 56 may be swung to one side or the other to an operative position away from its central neutral 60 inoperative position. As it is so swung the rocker 110 is swung thereby so that it assumes position at either side of the central position shown in Fig. 4. In plan as in Fig. 4 these positions are indicated by dot dash lines 110' and 110'', and the 65 positions of the stud 114 on the rocker are also shown by dot dash lines.

66 With the manual member and rocker in an operative position the driving mechanism may be engaged by oscillating member 72 by manually 70 engaging part 98 thereof. As member 72 oscillates the bolt 100 is urged forwardly by spring 108 so that the lips 108 thereof are in the path of stud 114, see Fig. 4.

75 Should it be necessary or desirable to release the manual member and to simultaneously disengage the driving mechanism the manual member is swung inwardly to its neutral inoperative position. As it swings stud 114 engages that lip of the bolt which is in its path of movement so 75

that member 72 is swung to its neutral inoperative position and bringing about disengagement of the driving mechanisms.

As member 72 swings to its neutral inoperative position the bolt is moved rearwardly away from the rocker by means of the cam 107 and pin 104 so that the manual member may be swung to an operative position without starting the driving mechanism.

10 Should it be desired while the manual member is in an operative position, with the rolls under tension, to either disengage the driving mechanism or to reverse the direction of rotation of the rolls without disturbing the manual member, the member 72 is oscillated to its central or neutral operative position for disengaging the driving mechanism and beyond to its other operative position to reverse the rolls.

When the manual member is in one operative position and the shifter is in another operative position the manual member may be released or if desired it may be swung from said one operative position to neutral and then to its other operative position. As it swings to said other operative position the stud 114 of the rocker 72 engages the innermost lip of the bolt 100 to depress the bolt so that it will lie behind stud 114. Then when the manual member is swung to neutral position the driving mechanism is disengaged.

While I have described the invention in great detail and with respect to a preferred form thereof, it is not desired to be limited thereto since many changes and modifications may be made therein without departing from the spirit and scope of the invention. What it is desired to claim and secure by Letters Patent of the United States is:

1. A wringer comprising in combination, a frame having a roll therein, a swingable frame member movable in said first frame between a central inoperative position and operative positions at the sides thereof, a manual member on said swingable member, a second roll in said swingable frame, pressure means adapted to put the rolls under pressure, engageable connections associated with the pressure means and swingable frame adapted to be engaged for applying pressure when said swingable frame is in an operative position, reversing driving mechanism for said rolls on said frame including engageable members and a shifter movable between operative and inoperative positions to engage and disengage said members, said shifter and swingable frame being independently movable from inoperative to operative positions, and engageable means associated with said swingable frame and shifter adapted and arranged to coact whereby the shifter is moved to inoperative position by the swingable frame when the latter is moved from operative to inoperative position and the swingable member may be moved to operative position subsequent to the shifter being moved to an operative position.

65 2. A wringer comprising in combination, a frame having a roll therein, a swingable frame member movable in said first frame between a central inoperative position and operative positions at the sides thereof, a manual member on said swingable member, a second roll in said swingable frame, pressure means adapted to put the rolls under pressure, engageable connections associated with the pressure means and swingable frame adapted to be engaged for applying pressure when said swingable frame is in an

operative position, reversing driving mechanism for said rolls on said frame including engageable members and a shifter movable between operative and inoperative positions to engage and disengage said members, said shifter and swingable frame being independently movable from inoperative to operative positions, and engageable means associated with said swingable frame and shifter adapted and arranged to coact whereby the shifter is moved by the swingable frame as it swings from an operative to inoperative position and the shifter may be moved between operative and inoperative positions with the said frame in either an operative or inoperative position.

3. A wringer comprising in combination, a frame having a roll therein, a swingable frame member movable in said first frame between a central inoperative position and operative positions at the sides thereof, a manual member on said swingable member, a second roll in said swingable frame, pressure means adapted to put the rolls under pressure, engageable connections associated with the pressure means and swingable frame adapted to be engaged for applying pressure when said swingable frame is in an operative position, reversing driving mechanism for said rolls on said frame including engageable members and a shifter movable between operative and inoperative positions to engage and disengage said members, said shifter and swingable frame being independently movable from inoperative to operative positions, and engageable means associated with said swingable frame and shifter adapted and arranged to coact whereby the shifter is moved to inoperative position by the swingable frame when the latter is moved from operative to inoperative position and the swingable member may be moved to operative position subsequent to the shifter being moved to an operative position, the said engageable means including a projection on the swingable member and a retractable member on the shifter engageable therewith.

4. A wringer comprising in combination, a frame having a roll therein, a swingable frame member movable in said first frame between a central inoperative position and operative positions at the sides thereof, a manual member on said swingable member, a second roll in said swingable frame, pressure means adapted to put the rolls under pressure, engageable connections associated with the pressure means and swingable frame adapted to be engaged for applying pressure when said swingable frame is in an operative position, reversing driving mechanism for said rolls on said frame including engageable members and a shifter movable between operative and inoperative positions to engage and disengage said members, said shifter and swingable frame being independently movable from inoperative to operative positions, and engageable means associated with said swingable frame and shifter adapted and arranged to coact whereby the shifter is moved to inoperative position by the swingable frame when the latter is moved from operative to inoperative position and the swingable member may be moved to operative position subsequent to the shifter being moved to an operative position, the said engageable means including a projection on the swingable member, a member slidably in the shifter for lying in the path of the projection when the shifter is in an operative position, and a cam to move the slidable member out of the path.

of said projection when the shifter is in an operative position.

5. A wringer comprising in combination, a frame having a roll therein, a swingable frame member movable in said first frame between a central inoperative position and operative positions at the sides thereof, a manual member on said swingable member, a second roll in said swingable frame, pressure means adapted to put 10 the rolls under pressure, engageable connections associated with the pressure means and swingable frame adapted to be engaged for applying pressure when said swingable frame is in an operative position, reversing driving mechanism for said rolls on said frame including engageable members and a shifter movable between operative and inoperative positions to engage and disengage said members, said shifter and swingable frame being independently movable from 15 inoperative to operative positions, a projection on said swingable frame member movable in a certain path as the said member moves between inoperative and operative positions, a member 20 slidable in said shifter having spaced parts adapted to lie in the path of movement of the projection, and means to control the position of said slidable member to position the said spaced parts in the path of movement of the projection when the shifter is in a certain position.

6. A wringer comprising in combination, a frame having a roll therein, a swingable frame member movable in said first frame between a central inoperative position and operative positions at the sides thereof, a manual member on 30 said swingable member, a second roll in said swingable frame, pressure means adapted to put the rolls under pressure, engageable connections 35 associated with the pressure means and swingable frame adapted to be engaged for applying pressure when said swingable frame is in an operative position, reversing driving mechanism for said rolls on said frame including engageable members and a shifter movable between operative and inoperative positions to engage and disengage said members, said shifter and swingable frame being independently movable from 40 inoperative to operative positions, a projection on said swingable member, a member slidable in the shifter, means urging said member into the path of movement of said projection, and cam means to move said slidable member out of the path of movement of the projection in certain positions of the shifter.

7. A wringer comprising in combination, a frame having a roll therein, a swingable frame member movable in said first frame between a central inoperative position and operative positions at the sides thereof, a manual member on 50

said swingable member, a second roll in said swingable frame, pressure means adapted to put the rolls under pressure, engageable connections associated with the pressure means and swingable frame adapted to be engaged for applying pressure when said swingable frame is in an operative position, reversing driving mechanism for said rolls on said frame including engageable members and a shifter movable between operative and inoperative positions to engage and 5 disengage said members, said shifter and swingable frame being independently movable from inoperative to operative positions, a projection on said swingable frame member movable in a certain path as the said member moves between 10 inoperative and operative positions, a member slidable in said shifter having spaced parts adapted to lie in the path of movement of the projection, and means to control the position of said slidable member to position the said spaced parts in the path of movement of the projection 15 when the shifter is in a certain position.

8. A wringer comprising in combination, a frame having a roll therein, a swingable frame member movable in said first frame between a central inoperative position and operative positions at the sides thereof, a manual member on said swingable member, a second roll in said swingable frame, pressure means adapted to put the rolls under pressure, engageable connections 25 associated with the pressure means and swingable frame adapted to be engaged for applying pressure when said swingable frame is in an operative position, reversing driving mechanism for said rolls on said frame including engageable 30 members and a shifter movable between operative and inoperative positions, to engage and disengage said members, said shifter and swingable frame being independently movable from inoperative to operative positions, a projection 35 on said swingable frame member movable in a certain path as the said member moves between inoperative and operative positions, a member slidable in said shifter having spaced parts adapted to lie in the path of movement of 40 the projection, and means to control the position of said slidable member to position the said spaced parts in the path of movement of the projection when the shifter is in a certain 45 position, said means including a spring for urging the slidable member in one direction and a cam for urging the same in an opposite direction.

JULIAN L. PERKINS.
